UNITED STATES PATENT OFFICE

WILLIAM G. LEET, OF SHREVEPORT, LOUISIANA, ASSIGNOR TO THE PITTSBURGH METER COMPANY, A CORPORATION OF PENNSYLVANIA.

SEPARATOR.

1,174,743.

Specification of Letters Patent.

Patented Mar. 7, 1916.

Application filed June 15, 1915. Serial No. 34,203.

To all whom it may concern:

Be it known that I, WILLIAM G. LEET, a citizen of the United States, and a resident of Shreveport, in the parish of Caddo and 5 State of Louisiana, have made a new and useful Invention in Separators, of which the following is a specification.

This invention relates to gas purifiers and particularly to means for purifying natural 10 gas as it issues from the wells or prior to delivering it to the distribution system.

An object of the invention is to produce a new and improved gas purifier or separator which is continuous in operation and is more 15 effective in extracting liquid and solid matters from the gas than other separators now in use or known to me.

The gas issuing from a gas well ordinarily carries or entrains solid material such as 20 sand and it is ordinarily saturated with condensable vapors which will condense at the pressures and temperatures ordinarily encountered in the distribution system. The necessity for removing these impurities 25 from the gas prior to delivering it to the distribution system is well known, and various types of purifiers, separators, extractors, etc., have been devised to accomplish the removal of the same, but so far as I 30 know, no entirely satisfactory apparatus had been employed up to the time of my present invention.

The apparatus heretofore used either are 35 ineffective in operation or they are objectionable by reason of the fact that they are complicated in structure and require special care and skill while in operation. In addition to this, there is, so far as I know, no commercial apparatus which is continuous 40 in operation and which is effective in simultaneously removing both the solids and liquids or condensable vapors from the gas.

A further object of my invention is therefore to produce a simple and effective continuously operating separator which will simultaneously remove both the solid and condensable vapors and liquid from the gas prior to delivering it to the distribution system.

50 These and other objects, which will be made apparent throughout the further description of my invention, are attained by means of apparatus embodying the features

herein described and illustrated in the drawing accompanying and forming a part 55 hereof.

In the single sheet drawing I have more or less diagrammatically illustrated one embodiment of my invention, but it will be apparent to those skilled in the art that 60 various changes, modifications, substitutions, additions and omissions may be made therein without departing from the spirit and scope of the invention as set forth by the claims which are appended hereto and form 65 a part hereof.

In the illustrated embodiment of the invention, gas from a source of supply, such for example as one or more wells, is received through a pipe line 4, in which is located a 70 pressure reducing device 5, here shown as a regulator, such as is ordinarily employed, which is adapted to throttle the flow of gas traversing the line 4 in such a way as to reduce its pressure to a pressure which is 75 desirable in the distribution system. While the regulator shown is of the type which automatically varies the amount of throttling of the gas or the amount of gas delivered in accordance with variations in the 80 pressure of the gas at the delivery port thereof, this refinement may not be essential in every embodiment of my invention, since, under some conditions, any pressure reducing device, which throttles the flow of gas 85 from the pipe line, may be employed.

The throttling of the gas as it passes through the pressure reducing device 5 occasions a forced expansion of the gas and the entrained condensable vapors, which 90 takes place at the expense of the heat stored in the gas. The expansion results in a material drop in the temperature of the gas which is sufficient, under the ordinary pressures encountered, to cause the entrained 95 condensable vapors, such as water vapor and vapors of relatively low volatile hydro-carbon liquids, to condense. In apparatus embodying my invention the reduction in the temperature of the gas and the resulting 100 condensation of the condensable vapors carried by the gas, together with the increase in the velocity of the gas, occasioned by the expansion, are employed in the removal of impurities from the gas. To this end a 105 separator chamber 6 is located immediately

adjacent to the pressure reducing device 5, and a nozzle 7, which receives the expanded gas delivered by the device 5, projects into the chamber 6 through an inlet port 8 with which the casing 9, inclosing the chamber, is provided. As illustrated, the nozzle 7 is turned so that its delivery end projects downwardly and discharges at a point within the chamber immediately above a decrement discharge port 10, with which the casing 9 is provided. As illustrated, the discharge end of the nozzle is slightly convergent so that the gas issuing therefrom is directed downwardly in a more or less solid stream toward the discharge port 10. With this arrangement the impurities carried by the gas are more or less concentrated and are discharged downwardly toward the discharge port 10. The upper end of the casing 9 is provided with a gas delivery port 11 through which the gas is delivered to a distributing main 12, and as illustrated, the casing 9 is provided with a series of baffle plates 15 which extend partially across the separator chamber and provide an extended surface on which the moisture carried by the gas traversing the separator chamber may collect.

As illustrated, the discharge port 10 is located at the lowest point of the casing 9 and is connected by means of a short pipe section 13 to a receptacle or reservoir 14, which is located below the casing 9. With this arrangement the impurities, carried by the gas issuing from the nozzle 7, will be discharged into the receptacle 14 by reason of the fact that they are projected from the nozzle at a high velocity and their inertia tends to cause them to continue their downward motion, whereas the gas itself, issuing from the nozzle, first comes to rest within the casing 9 and then reverses its direction of flow and proceeds toward the delivery port 11 of the casing. The pipe section 13 is preferably axially alined with the delivery end of the nozzle 7 so that the impurities carried by the gas will be discharged from the nozzle directly through the section 13 into the receptacle 14. The discharge end 50 of the nozzle 7 is preferably so located within the casing that the reversal in flow of the gas will take place wholly within the casing but in the immediate neighborhood of the port 10, since a reversal in flow of the gas 55 within the pipe section 13 will tend to impede the delivery of impurities through the port 10.

The reservoir 14 is in effect a decrement receiving receptacle into which the sand or 60 solid particles, liquid and the condensed vapors are discharged. The details of construction of this receptacle are not of material importance, so long as it is located below the discharge port 10 and it is provided 65 with a decrement discharge port located at

or near the lowest portion of the reservoir through which a continuous flow of liquid may pass. It is essential, however, that this reservoir be of sufficient capacity to take care of large quantities of water which may be delivered from the wells through the field lines, to the separator, since when water is encountered in large quantities it is invariably delivered through the field lines in "headers" or waves. The reservoir 14-75 should therefore be of sufficient capacity to receive the "headers" or waves of water and to prevent them from interfering with the normal operation of the apparatus. In some installations I find that a section of relatively large pipe provides an adequate reservoir 14, and I have also found that it may be desirable to provide means for flushing out this reservoir with liquid other than that received from the chamber 6. 85

In the drawing I have illustrated the reservoir provided with a flush pipe 16, through which water may be delivered. The reservoir is also provided with a decrement discharge port 17, which is shown connected 90 by means of piping 18, to a pressure regulator or reducing valve 19, the discharge port of which communicates with a second reservoir or receptacle 21. This reservoir 21 is usually located at a level above that of the reservoir 14, since the reservoir 14 is ordinarily located so far below the surface of the ground that it would be impractical to drain the reservoir 21 if it were on a level with the reservoir 14. The reservoir 21 is provided with a discharge port 22 which is in open communication with one leg of a trap 23, the other leg of which communicates with a discharge pipe 24, from which the water, liquid and solid matter separated 105 from the gas are discharged. The trap 23 is of sufficient depth to prevent gas bubbling through it to the atmosphere.

As illustrated, the regulator 19 is of the type provided with an operating diaphragm 110 which is located in a pressure chamber 19^a. The upper face of the diaphragm or the upper portion of the chamber 19^a is placed in communication with the reservoir 21 or with the delivery port of the regulator 19 by means of piping 26. This piping is provided with a restricted discharge port 25, which may be controlled by a needle valve and through which gas delivered to the reservoir 21 with the water is discharged. 115 The operation of the regulator 19 is as follows: So long as liquid is discharged from the reservoir 14 through the piping 18, the regulator 19 will remain open, since the water delivered by it to the reservoir 21 will 120 exert no back pressure in the reservoir 21 and consequently will not actuate the diaphragm contained within the chamber 19^a. 125 As soon as gas is delivered through the regulator 19 to the reservoir 21, the pressure 130

in this reservoir piles up, due to the fact that the column of liquid within the trap 23 prevents the discharge of the gas to the atmosphere. This gas pressure within the reservoir 21 is transmitted to the actuating diaphragm of the regulator 19 through the piping 26, and is effective in closing the regulator and thereby shutting off communication between the reservoirs 14 and 21.

10 By this arrangement the waste of gas is limited to the relatively small quantities which may discharge through the restricted port 25 and the gas pressure within the reservoir 21 cannot pile up sufficiently to cause gas to bubble through the trap 23. As soon as the gas pressure in the reservoir 21 has decreased sufficiently to permit the opening of the regulator 19, the regulator will open and remain open provided a continuous flow of liquid is delivered to it through the piping 18.

The operation of the apparatus is as follows: Let it be assumed that the gas in the pipe line 4 is at a pressure of 100 pounds 25 and that it is desirable to maintain a pressure of approximately 20 pounds in the distributing system. The pressure reducing device 5 will, therefore, be adjusted so as to maintain a pressure of approximately 30 20 pounds in the chamber 6. The gas delivered by the device 5 increases materially in volume or expands because of the lower pressure encountered within the chamber 6, and this expansion, as has been described, 35 results in a drop in temperature and of course an increase in the velocity of flow through the nozzle 7. This reduction in temperature occasions a condensation of the condensable vapors carried by the gas, which 40 takes place prior to the discharge of the gas from the nozzle 7. The liquids resulting from the condensation and the liquids carried by the gas are collected in small globules or, if sufficient liquid is present, into a 45 stream by reason of the fact that the delivery end of the nozzle is convergent. These liquids are heavier than the gas and by reason of their inertia, drop to the bottom of the chamber 6 or are discharged 50 through the port 10 at the time of reversal in flow of the gas issuing from the nozzle. This moisture in the gas, the high velocity 55 of flow as the gas issues from the nozzle 7, and the reversal of flow of the gas within the chamber 6 are effective in separating the solid matter, such as sand, mud, etc., from the stream of gas. The liquid carried by the gas tends to collect on any solid particles entrained by the gas and to thereby 60 increase their weight. At the time of reversal in flow of the gas the solid particles resist a change in the direction of their motion by reason of their inertia and consequently either fall through the port 10, 65 or collect on the bottom of the chamber 6,

from which they are washed by the accumulation of moisture. When it is understood that the gas practically comes to rest at the time of reversing its flow, or in other words, at the time of changing its direction of motion from that toward the bottom of the chamber 6 to a motion toward the port 11 at the top of the casing, it will be clearly understood that gravity will effect the desired separation from the gas of the liquids carried by the gas, condensed liquids and solid matter. In addition to this, the gas in leaving the chamber 6 traverses a circuitous path, by reason of the arrangement of baffles 15, in which its direction of flow is reversed a number of times and in which it is exposed to a relatively large wetted surface which will have a high affinity for the moisture carried by the gas and will be effective in removing substantially all of the moisture from the gas before it reaches the port 11.

The liquids, condensed liquids and the solid matter separated from the gas will eventually collect in the receptacle 14 from 90 which they are forced through the reducing valve 19 into the elevated receptacle 21 by the pressure of the gas within the chamber 6. The valve 19 is preferably set to reduce the pressure from 20 pounds in the reservoir 14 95 to a pound or less in the reservoir 21. Under ordinary conditions there will be sufficient moisture separated from the gas to cause a continuous flow of liquid through the port 17 and to carry the solid matter with it from 100 the receptacle 14, but as previously described this receptacle may be periodically flushed without interfering with the operation of the separator. Under ordinary conditions there will be a continual flow of liquid through 105 the receptacles 14 and 21 and consequently these liquids together with the solid matter will pass to the trap 23 and be discharged. If, however, the flow of liquid to the reservoir 21 ceases, because the liquid in the reservoir 110 21 is exhausted, gas will pass to the reservoir 21, and, as before described, will actuate the regulator 19 to close communication between the reservoirs 14 and 21. As soon as the gas pressure within the reservoir 21 again decreases, due to the leakage of gas through the port 25, the regulator will again open and will remain open if a continuous flow of liquid is delivered to it from 115 the reservoir 14.

The principal features of my invention are that the apparatus embodying it is simple both in construction and in operation; the condensable vapors, liquid and solid matter carried by the gas are simultaneously abstracted; the liquids separated from the gas are effective in accomplishing the necessary washing of the gas and the separation of the solid matter, and the apparatus is continuous in operation and is self cleaning.

Having now described one embodiment of my invention, what I claim is:

1. A separator having a gas admission port communicating with the source of gas supply, a gas delivery port communicating with the distribution system, and a recrement discharge port, and a pressure reducing device between the admission port of said separator and the source of gas supply, so located with reference to the separator that the drop in temperature occasioned by the passage of gas through said pressure reducing device is employed in the removal of condensable vapors from the gas as it traverses the separator.
2. In combination with a source of gas supply, a pressure reducing device to which gas from said source is delivered, a separator chamber located adjacent to said device, a nozzle projecting downwardly within said chamber and communicating with said device, a recrement receptacle located below said chamber and in open communication with a recrement discharge port with which the chamber is provided.
3. In combination with a source of gas supply, a separator chamber having a gas admission port, a gas delivery port and a recrement discharge port, a pressure reducing device between the admission port of said chamber and the source of gas supply, so located with reference to said chamber that the reduction in temperature occasioned by the expansion of the gas passing said device is effective in condensing the condensable vapors carried by the gas entering said chamber, a downwardly projecting nozzle located within said chamber, discharging near the bottom of said chamber and receiving expanded gas delivered by said device, and a seal for said discharge port.
4. In a gas separator comprising a separator chamber having a gas delivery port located near the upper end thereof and a continuously open recrement discharge port located in the bottom of the chamber, a gas delivery nozzle projecting into said chamber and having its discharge end near the bottom of the chamber, a pressure reducing device between the source of gas supply and the chamber located immediately adjacent to the chamber and communicating with said nozzle, and a liquid seal for said recrement discharge port.
5. A gas separator, comprising a separating chamber having a gas delivery port located near the upper end thereof and a recrement discharge port located in the bottom thereof, a source of gas supply, a pressure reducing device between said source of supply and said chamber, and a nozzle communicating with said device and projecting into said chamber with its discharge end located near the bottom of the chamber.
6. In combination with a gas separator, a recrement receiving reservoir communicating with the recrement discharge port of the chamber, a regulator between said recrement discharge port and said reservoir, and means responsive to the pressure of gas delivered by the regulator to the reservoir for actuating the regulator to close communication between the port and the reservoir.

In testimony whereof, I have hereunto subscribed my name this 2nd day of June, 1915.

WILLIAM G. LEET.
